(57) **CLAIM**

I claim the ornamental design for a handheld vaping implement, as shown and described.

DESCRIPTION

FIG. 1 illustrates an isometric view of a handheld vaping implement showing my design;

FIG. 2 is a left elevation view thereof;

FIG. 3 is a top plan view thereof;

FIG. 4 is a front elevation view thereof;

FIG. 5 is a bottom plan view thereof;

FIG. 6 is a right elevation view thereof; and,

FIG. 7 is a rear elevation view thereof.

The broken lines in the drawings illustrate portions of the handheld vaping implement that form no part of the claimed design.
